Primary Examiner—Louis S. Zarfas*Assistant Examiner*—Monica A. Weingart*Attorney, Agent, or Firm*—Richard C. Litman[57] **CLAIM**

The ornamental design for a bow holder, as shown and described.

DESCRIPTION

FIG. 1 is an environmental perspective view of a bow holder showing our new design;

FIG. 2 is an environmental front elevational view thereof;

FIG. 3 is an environmental rear elevational view thereof;

FIG. 4 is an environmental left side elevational view thereof;

FIG. 5 is an environmental right side elevational view thereof;

FIG. 6 is an environmental top plan view thereof; and,

FIG. 7 is an environmental bottom plan view thereof.

The broken line showing of the rail and the bow in FIG. 1 is for illustrative purposes only and forms no part of the claimed design. The broken line showing of the clamp in FIGS. 1–7 is for illustrative purposes, merely showing the types of attachments which can be used, and forms no part of the claimed design.
